(57) **CLAIM**

The ornamental design for a faux bois bench, as shown and described.

DESCRIPTION

FIG. 1 is a perspective view of a faux bois bench with tags. That portion of the faux bois bench behind the left tag is identical to the corresponding portion of the faux bois bench of FIG. 2. That portion of the faux bois bench behind the right tag is identical to the corresponding portion of the faux bois bench of FIG. 2.

FIG. 2 is a perspective view of the faux bois bench of FIG. 1 without tags; and,

FIG. 3 is a back view of the faux bois bench of FIG. 1 with a second faux bois bench in the background.

The tags on the faux bois bench of FIG. 1 form no part of the claimed design.
